UNITED STATES PATENT OFFICE.

JOSEPH A. SHUART, OF SACRAMENTO, CALIFORNIA.

FIRE-ESCAPE.

1,114,392.

Specification of Letters Patent. Patented Oct. 20, 1914.

Application filed December 13, 1913. Serial No. 806,591.

To all whom it may concern:

Be it known that I, JOSEPH A. SHUART, a citizen of the United States, residing at Sacramento, in the county of Sacramento and State of California, have invented certain new and useful Improvements in Fire-Escapes; and I do hereby declare the following to be a full, clear, and exact description of the invention, such as will enable others skilled in the art to which it appertains to make and use the same.

My invention relates to new and useful improvements in fire escapes.

An important object of my invention is to provide novel means for supporting a person or persons desirous of making a descent from burning buildings to the ground, which slidably engages a guide rope and is provided with novel friction brake means for governing the speed of the descent.

Another important object of my invention is to provide a device of the character described which consists of a plate having a plurality of openings therein through which a guide rope is adapted to be intertwined so that the plate is permitted free sliding movement on the guide rope, said plate adapted to have secured thereto a supporting band or the like whereby a person may make a rapid and safe descent.

Another important object of the invention is to provide a fire escape of the character described which employs novel friction brake means consisting of a pair of jaws, one fixed integral with the plate and the other pivoted thereon that are adapted to grip the guide rope so that regulation of the speed of the descent may be readily had.

This invention further aims to improve devices of the above mentioned character so as to render them more practical, reliable and efficient in operation, simple as to construction and number of parts and more commercially desirable.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which

similar reference numerals designate corresponding parts: Figure 1 is a top plan view of my device as it would appear in assembled position, Fig. 2 is a longitudinal sectional view taken on line 2—2 of Fig. 1, 60 showing the rope intertwined in the plate and the friction brake, and Fig. 3 is a sectional view taken on line 3—3 of Fig. 1 illustrating the detail construction and arrangement of the gripping jaws of the friction 65 brake.

Referring now to the drawings forming a part of this specification and in which like numerals are employed to designate corresponding parts, the numeral 1 designates as an entirety a rectangular plate formed of suitable metal that is provided with a plurality of round edged openings 2 arranged in spaced relation in the plate. This plate 1 is adapted to have a guide rope 75 designated 4 intertwined through the openings 2 therein so that the plate is permitted free movement on the guide rope.

A belt designated 5 as an entirety and provided with a suitable buckle not shown 80 and a snap hook 6 is adapted to be connected with the plate 1 and is arranged to support a person or persons in preferably a sitting posture. This belt 5 is connected preferably with the lowermost of the openings 85 2 in the plate 1 by snapping the hook 6 within the opening.

Mounted centrally of the ends of the plate 1 is a friction brake mechanism designated as an entirety by the numeral 7. This friction brake mechanism 7 consists of a fixed 90 jaw 8 and a pivoted jaw 9. The fixed jaw 8 is provided with an integral handle portion 10 that extends outwardly from the plate 1 at right angles thereto. The pivoted 95 jaw is provided with an integral handle 11 extending outwardly from the plate 1 in parallel spaced relation to the handle 10. These handles 10 and 11 are preferably bowed intermediate the ends to facilitate a 100 greater leverage for the jaws 8 and 9.

The central portion of the plate is hollowed out as at 12 forming acute angle edges 13 and 14, as shown in Fig. 2 in the drawings, to a middle portion 8 which may be 105 considered as one jaw; opposed to which is pivoted a cylindrical bar 9, forming another jaw. Between these jaws the rope is gripped and as it is then carried through the plate 1 at each side of the jaw 8 the edges 13 and 14 110

of such jaw have a biting engagement therewith.

A pair of spaced apertured supporting ears 16 are formed adjacent one edge of the plate 1 and are adapted to receive an ear 17 on the free end of the jaw 9, therebetween so that a pivot pin 18 may be inserted through the ears 16 and 17 for the purpose of pivotally connecting the jaw 9 and handle 11 to the plate 1. It will be further noted that the operator in grasping the handles 10 and 11 which are disposed at right angles to the plate 1 and rope 4, to apply the friction brake as hereinbefore described, 15 may owing to the connection of the handles 10 and 11 to the plate 1, move the plate angularly with relation to the line of descent thus producing great friction and assisting the jaws 8 and 9 in their braking action.

20 It will be apparent with reference to the foregoing description and drawings that there has been provided a fire escape which is simple as to construction and number of parts and that is reliable and efficient in its 25 operation and capable of performing all functions hereinbefore described in a reliable and expeditious manner.

In reduction to practice, I have found that the form of my invention, illustrated in the 30 drawings and referred to in the above description, as the preferred embodiment, is the most efficient and practical; yet realizing that the conditions concurrent with the adoption of my device will necessarily vary, 35 I desire to emphasize the fact that various minor changes in details of construction, proportion and arrangement of parts may be resorted to, when required, without sacri-

ficing any of the advantages of my invention, as defined in the appended claims.

What is claimed is:—

1. In a device of the character described, the combination with a guide rope, of a plate having a plurality of openings therein to slidably receive the guide rope, a belt for supporting a person secured to said plate, and a brake member secured to said plate, a fixed bar or jaw centrally of the plate having a central depression therein, a pivoted bar or jaw extending in parallel relation to said fixed jaw and pivotally secured to the plate, said guide rope being disposed between the fixed and pivoted jaws, said pivoted jaw having a convex gripping face, parallel biting edges formed by the depression in the fixed jaw, and integral handles on the fixed and pivoted jaws extending outwardly at right angles to the plate upon one side thereof.

2. In a device of the character described, the combination with a guide rope, of a plate having a plurality of openings therein to slidably receive the guide rope, a handle extending outwardly at right angles to the plate, the central portion of the plate being hollowed out to provide acute angle edges to a middle portion, a cylindrical bar pivoted to the plate and co-operating with the acute angle edges to grip the rope and belt to support a person secured to the plate.

In testimony whereof I affix my signature in presence of two witnesses.

JOSEPH A. SHUART.
